CLAIM

The ornamental design for a grooming device holder, as shown and described.

DESCRIPTION

FIG. 1 is a perspective view of a grooming device holder according to the present invention;

FIG. 2 is a front view thereof;

FIG. 3 is a top view thereof;

FIG. 4 is a bottom view thereof;

FIG. 5 is a first side view thereof;

FIG. 6 is a second side view thereof;

FIG. 7 is a rear view thereof; and,

FIG. 8 is a perspective view of the grooming device holder shown with the cover removed in a state of use.

The ornamental design which is claimed is shown in solid lines in the drawings. The broken line accessories that are shown in FIG. 8 illustrate the environment and form no part of the claimed design. The remaining broken lines that are shown on the body of the grooming device holder illustrate portions of the article and form no part of the claimed design.
